UNITED STATES PATENT OFFICE.

OLE J. MYERS, OF YOUNGSTOWN, OHIO

CONCRETE TIE AND STEEL PLATE.

1,055,211.

Specification of Letters Patent.

Patented Mar. 4, 1913.

Application filed December 3, 1912. Serial No. 734,751.

To all whom it may concern:

Be it known that I, OLE J. MYERS, a citizen of the United States, residing at Youngstown, in the county of Mahoning and State of Ohio, have invented new and useful Improvements in Concrete Ties and Steel Plates, of which the following is a specification.

This invention relates to a combined rail tie and rail fastener; and it has for its object the provision of a tie which may be constructed of concrete or like plastic material and which will include reinforcing elements embedded in the material and terminally extended therefrom whereby to form fastening portions to which may be secured companion rail clamping plates.

A still further object of the invention is the provision of a tie wherein the rail fastening plates thereof will be positively held against creeping longitudinally on the tie.

With these and other objects in view, the invention consists of certain novel features of construction, combination and arrangement of parts, as will be hereinafter described and claimed.

In the accompanying drawings:—Figure 1 is a top plan view of the tie, showing the manner of connecting the rails thereto; Fig. 2 is a section on line 2—2 of Fig. 1; Fig. 3 is a section on line 3—3 of Fig. 2; Fig. 4 is a section on line 4—4 of Fig. 2; and Fig. 5 is a section through a portion of a tie, showing the manner of connecting the fish plates therewith and with adjacent ends of the rail.

The tie 1 which is constructed of concrete or plastic fire-proof material has embedded therein longitudinal metallic rods 2, which are spaced relatively and disposed adjacent to the longitudinal sides of the tie, as clearly shown in Fig. 4 of the drawings, while similar reinforcing rods 3 are located above the plane of the first rods and spaced therefrom through the provision of substantially U-members 4. These members are constructed preferably of iron rods and are shown to include vertical legs 5, which are twisted at 6 around the adjacent bars 2 and 3 whereby to combine therewith to form an efficient reinforcing frame within the tie, as is evident.

The said side legs 5 are terminally extended above the plane of the upper surface of the

tie where they are threaded as at 7, for a purpose to be hereinafter described. Similar U-members 4^a are intertwisted at 8 with the upper bars 3 and connected at 9 with substantially arched bars 10. The bars 10 extend longitudinally of the tie and they are terminally connected with the lower bars 2 preferably at the points of connection of the latter with the vertical legs 5 of the first described U-members 4. The vertical legs 11 of the U-members 4^a are terminally disposed above the plane of the upper surface of the tie and as shown they are located immediately opposite the threaded extremities 7 of said first members.

With reference to Fig. 1, it is seen that the companion rails A are extended across the tie and disposed immediately between the companion threaded extremities of the U-members 4 and 6, said extremities being extended through passages 12 in clamping plates 13. The plates are thus disposed at the opposite sides of the rail and they may be secured in place thereagainst through the medium of clamping nuts 14, the latter being associated with the threaded extremities of said U-members, as clearly disclosed in Fig. 2. The fish plates 15 are bolted at 16 in the usual manner to the rail ends and they are preferably provided with extensions 17 having vertical passages 18 therein to receive the vertical extremities of the U-members.

From the construction described, it is seen that an exceedingly simple, strong, durable, fire and weather-proof tie is provided, wherein the rail fastenings thereof serve to effectually hold the rails of the track against spreading relatively.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as claimed.

Having thus described my invention, what I claim is:—

A tie comprising a plastic body, a metal-

lic frame embedded within the body and including longitudinal upper and lower bars and longitudinal arched bars, and substantially U-members connected with the longitudinal bars and including vertical legs terminally disposed beyond the rail supporting surfaces of the tie.

In testimony whereof I affix my signature in presence of two witnesses.

OLE J. MYERS.
